WILLIAM J. NEWTON, OF BRIDGEPORT, CONNECTICUT, ASSIGNOR TO HARVEY HUB-BELL, INCORPORATED, OF BRIDGEPORT, CONNECTICUT, A CORPORATION OF CONNECTICUT.

SURFACE TOGGLE-SWITCH.

1,361,170.

Specification of Letters Patent.

Patented Dec. 7, 1920.

Application filed January 13, 1920. Serial No. 351,271.

To all whom it may concern:

Be it known that I, WILLIAM J. NEWTON, a citizen of the United States, residing at Bridgeport, county of Fairfield, State of Connecticut, have invented an Improvement 5 in Surface Toggle-Switches, of which the following is a specification.

This invention has for its object to improve the construction and mode of operation 10 of surface toggle switches and with these ends in view I have devised the novel structure which will be hereinafter fully described.

In the accompanying drawing forming a 15 part of this specification,

Figure 1 is a plan view of my novel switch as in use;

Fig. 2 a section on line 2—2 in Fig. 1, looking in the direction of the arrows;

20 Fig. 3 a plan view of the base and its spring contact plates;

Fig. 4 an enlarged sectional view on the line 4—4 in Fig. 1, looking in the direction of the arrows;

25 Fig. 5 a perspective view of the bracket on which the operating lever is pivoted;

Fig. 6 a perspective view of the contact arm; and

Fig. 7 is a perspective view of the lower 30 member of the toggle.

10 denotes the base, 11 the frame, 12 the contact arm, 13 the operating lever which is pivoted on a bracket 14 in a hub 15 on the frame, and 16 the cap which is provided 35 with an insulating lining 17 and the edge of which engages the base. The cap is retained in place by means of a central in-turned collar having threaded engagement with the hub.

40 The frame is provided with lugs 18 and is secured to the base by means of screws 19.

At diametrically opposite sides of the frame are holes 20 the purpose of which will be hereinafter explained. The bracket 14

45 comprises a disk shaped part 21 which fits into hub 15, and downwardly extending lugs 22. The disk shaped part of the bracket has therein a rectangular hole 23 of sufficient dimensions for the passage and

50 throw of the operating lever, and diametrically across it is a depression 24 in which rests the pivot pin 25 of the operating lever.

In the lugs 22 are holes 26.

The contact arm comprises a strip of 55 metal bent to U-shape, the bridge portion of

said arm being indicated at 27. The branches 28 of the contact arm straddle the inner arm of the operating lever and are carried by a pin 29 which passes through holes 20 and 26 in the frame and bracket, 60 respectively, and holds these parts together. The metal bearings 30 for said contact arm are insulated from the branches thereof.

The toggle 31 consists of the inner arm of the operating lever and the insulating toggle arm 32. The inner arm of the operating lever extends between the branches of the contact arm and is provided with an arcuate slot 33 through which pin 29 passes, and the ends of which limit the throw of the operating lever. The insulating toggle arm is composed of two strips 34 held together by a plate 35, and having thereon heads 36, all of some insulating material, such as fiber. The strips are passed through holes 37 in 75 the plate and the heads rest thereagainst, as clearly shown. The heads are arranged on opposite sides of the inner end of the inner arm of the operating lever, and have therein notches 38 to receive a cross pin 39 carried by said inner end and extending beyond the sides thereof. The outer ends of strips 34 are passed through holes 40 in the bridge portion of the contact arm. A relatively strong coil spring 41 surrounds the strips 80 and bears respectively against plate 35 and said bridge portion. It will be seen that the structure is such that when lever 13 is operated, the heads will pass beneath pin 29 and between the branches of the contact arm 85 from one side thereof to the other.

The arc slot in the inner arm of the operating lever lies between the pivot pin of said lever and cross pin 39, the mid point of said slot being in alinement with said pivot pin 90 and cross pin.

42 and 43 denote the spring contact plates and 46 and 47 are binding posts carrying binding screws 44 to which wires, not shown, passing through holes 45 are attached. It 100 will be understood that in the closed circuit position of the contact arm the outer portions of the branches thereof will be in engagement with the spring contact plates and the current will pass from one of said plates 105 to the other through the bridge portion of the contact arm.

The operation will be perfectly clear from the description already given. The different views show the contact arm in open cir- 110

cuit position. The spring 41 is exerting pressure against the bridge portion of the contact arm and against cross pin 39, thereby holding one end wall of the slot in the 5 operating lever against pin 29, and the contact arm in one of its extreme positions. Movement of the operating lever from the position shown to the reverse position will move the strips outward against the power 10 of the spring, the outer ends of the strips sliding through the holes in the bridge portion. This movement will continue until the insulating toggle arm, cross pin 39 and pin 25 for the operating lever are in alignment. An instant later the compression of 15 the spring will act to swing the contact arm to the other extreme of its movement and close the circuit, the relative positions of the insulating toggle arm, cross pin and pivot 20 for the operating lever being now reversed. In practice, the contact arm will remain in either the open circuit or closed circuit position until the toggle swings past its dead center, when the expansion of the spring 25 will instantly throw the toggle to the reverse position with a snap.

The invention provides a very simple construction of surface toggle switch.

What I claim is:

30 1. A mechanism of the character described, comprising an operating lever having an arcuate slot, a U-shaped contact arm whose branches straddle the inner arm of the operating lever, a pin carrying said 35 branches and riding in said slot, and a spring controlled insulating toggle arm bearing against the inner arm of the operating lever and having sliding connection with the contact arm.

40 2. A mechanism of the character described, comprising an operating lever having an arcuate slot, a contact arm carried by a pin which rides in said slot, and a spring controlled insulating toggle arm 45 bearing against the inner arm of the operating lever and having sliding connection with the contact arm.

3. A mechanism of the character described, comprising a pivoted operating 50 lever having a pin at the inner end of its inner arm, and intermediate said pin and its pivotal point an arcuate slot, a contact arm carried by a pin which is adapted to ride in said slot, and a spring controlled insulating 55 toggle arm, one end of which engages the first mentioned pin, the other end having sliding connection with the contact arm.

4. A mechanism of the character described, comprising an operating lever having an arcuate slot, a contact arm carried by a pin which rides in said slot, an insulating toggle arm consisting of strips of insulating material having heads and an insulating plate having slots through which the

strips pass and which is engaged by the 65 heads, said member bearing against the inner arm of the operating lever and having sliding connection with the contact arm, and a spring bearing against said plate and against the contact arm. 70

5. A mechanism of the character described, comprising an operating lever having an arcuate slot, a contact arm carried by a pin which rides in said slot, and a spring controlled insulating toggle arm 75 bearing against the inner arm of the operating lever and forming therewith a toggle, said insulating toggle arm having sliding connection with the contact arm.

6. A mechanism of the character de- 80 scribed, comprising an operating lever having an arcuate slot, a contact arm carried by a pin which is adapted to ride in said slot, an insulating toggle arm consisting of strips 85 of insulating material having heads and an insulating plate having slots through which the strips pass and which is engaged by the heads, said insulating toggle arm bearing against the inner arm of the operating lever and forming therewith a toggle, and a spring 90 bearing against said plate and against the contact arm.

7. A mechanism of the character described, comprising an operating lever having an arcuate slot and a pin at the inner 95 end of its inner arm, a U-shaped contact arm provided with branches and a bridge portion having slots therein, a pin extending through the branches and through the arcuate slot, and an insulating toggle arm, 100 the inner arm of the operating lever and the insulating toggle arm comprising a toggle, said insulating toggle arm consisting of strips of insulating material having slotted heads and an insulating plate having slots 105 through which the strips pass and which is engaged by the heads, the slots in the heads engaging the pin on the operating lever and the strips passing through the slots in the bridge portion of the contact arm, and a 110 spring bearing against said bridge portion and against the plate of the insulating toggle arm.

8. A mechanism of the character de- 115 scribed, comprising a pivoted operating lever having a pin at the inner end of its inner arm, and intermediate said pin and its pivotal point an arcuate slot, a U-shaped contact arm provided with branches and a bridge portion having slots therein, a pin 120 extending through the branches and through the arcuate slot, and an insulating toggle arm, the inner arm of the operating lever and the insulating toggle arm comprising a toggle, said insulating toggle arm consisting of strips of insulating material having slotted heads and an insulating plate having 125 slots through which the strips pass and

which is engaged by the heads, the slots in the heads engaging the pin on the operating lever and the strips passing through the slots in the bridge portion of the contact arm, and a spring bearing against said bridge portion and against the plate of the insulating toggle arm.

9. A mechanism of the character described, comprising a pivoted operating lever having a pin at the inner end of its inner arm, and intermediate said pin and its pivotal point an arcuate slot, a U-shaped contact arm provided with branches and a bridge portion having slots therein, a pin 15 extending through bearings in the branches and through the arcuate slot, said bearings being insulated from said branches, and an insulating toggle arm consisting of strips of insulating material having slotted heads and 20 an insulating plate having slots through which the strips pass and which is engaged by the heads, the slots in the heads engaging the pin on the operating lever and the strips passing through the slots in the bridge portion 25 of the contact arm, and a spring bear-

ing against said bridge portion and against the plate of the insulating toggle arm.

10. A mechanism of the character described, comprising a pivoted operating lever having a pin at the inner end of its inner arm, and intermediate said pin and its pivotal point an arcuate slot, a U-shaped contact arm provided with branches and a bridge portion having slots therein, a pin 30 extending through bearings in the branches and through the arcuate slot, said bearings being insulated from said branches, and an insulating toggle arm consisting of strips held together by a plate and carrying heads thereon, all of insulating material, said strips 35 carrying a spring the ends of which seat against said plate and the bridge portion of the contact arm, respectively, the outer ends of said strips sliding through the slots in the bridge portion and the heads having therein 40 slots for engaging the pin in the operating lever.

In testimony whereof I affix my signature.

WILLIAM J. NEWTON.
